UNITED STATES PATENT OFFICE

HENRY P. TAYLOR, OF WINSTON-SALEM, NORTH CAROLINA

PROCESS FOR PRESSING AND PACKING MANUFACTURED TOBACCO

Application filed August 17, 1929. Serial No. 386,519.

This invention relates to a method of pressing and packing manufactured tobacco such as plug and twist tobacco, and the object of the invention is to provide a method and a means of pressing and packing tobacco so as to eliminate the slick appearance of the end plugs which are prevalent in many forms of packing tobacco.

An object of my invention is to provide means whereby plug and twist tobacco can be pressed in the conventional way with slick press heads in the powerful hydraulic press, and then the mass of pressed tobacco can be placed in a caddy and said caddy placed in another press and the caddy is sealed under pressure with resilient fibrous spongy pads placed between the top and bottom members of the caddy or box and the tobacco and pressure applied so that a rough and ready surface will be imparted to the end plugs of tobacco so that said end plugs will have not only the appearance but also the quality of the plugs taken from the interior of the mass of pressed tobacco.

Another object of my invention is to provide means for pressing and packing manufactured tobacco in caddies, boxes and the like which comprises partially pressing the mass of tobacco in one press and then placing a caddy or box in another press with a spongy, resilient, fibrous pad in the bottom of the caddy or box next to the bottom member of this caddy or box so that this pad will be between the bottom member of the caddy or box and the bottom end plugs of the mass of partially pressed tobacco and then placing the mass of partially pressed tobacco in this caddy or box and then placing another spongy, resilient, fibrous pad on the top end plugs of the mass of partially pressed tobacco and then placing the head member of the caddy or box on top of the second spongy, resilient, fibrous pad and then finishing the pressing operation in the second press and sealing this head member of the caddy or box so that even if the mass of tobacco is first partially pressed in a press which has slick heads, as are commonly used, that the final operation of pressing the tobacco in a caddy or box and sealing the caddy or box, while under

pressure with the spongy, resilient, fibrous pads next to the tobacco, will cause the end plugs of tobacco to have a rough and ready appearance and simulate the appearance of plugs taken from the interior of the mass of tobacco.

Another object of my invention is to provide means whereby plug and twist tobacco can be pressed in the conventional way with slick press heads in the powerful hydraulic or power press and then the mass of pressed tobacco can be placed in a caddy, with resilient fibrous, spongy pads placed between the top and bottom members of the caddy or box and the pressed mass of tobacco, and the said caddy or box with the resilient fibrous, spongy pads and pressed mass of tobacco in it is then placed in another press and the head or top member of the caddy is sealed in place under pressure so that a rough and ready surface will be imparted in the end plugs of tobacco resulting in said end plugs having not only the appearance, but also the quality of the plug taken from the interior of the mass of pressed tobacco.

Some of the objects of my invention having been stated, other objects will appear as the description proceeds, when taken in connection with the accompanying drawings, in which—

Figure 1 is a cross-sectional view taken thru the front portion of a press, showing the first step in my process;

Figure 2 is a view of a slightly different form of press in which the tobacco is ready for the final pressing operation;

Figure 3 is a view similar to Figure 2, but showing the second pressing operation completed and the caddy sealed;

Figure 4 is an edge view showing in enlarged scale one of my spongy, resilient, fibrous pads after the same has been sealed in a caddy;

Figure 5 is a view of one of my spongy resilient fibrous pads before the same has been used.

Referring more specifically to the drawings, the numerals 10 and 11 indicate the supports of the press and shows only a portion thereof, and these supports have the projec-

tions 12 and 13 thereon on which the projections 14 and 15 on the press proper 16 are adapted to rest. The upper press head 17 is usually fixed in the conventional press, and the press head 18 is the movable one, this being propelled by hydraulic or other suitable power to compress the mass of plugs of tobacco, which mass of plugs of tobacco is indicated by the reference character 33. This is the conventional type of press in which tobacco is pressed prior to its being placed in another press for sealing, in which second press the caddy or box is placed and into this caddy or box the mass of tobacco 33 is placed for the sealing operation.

In Figure 2 I have shown a conventional type of press used for the sealing operation and into which the caddy is adapted to be placed, and in this type, the reference characters 20 and 21 indicate the supports for the press, which supports have the projections 22 and 23 thereon on which the projections 24 and 25 on the press casing 26 are adapted to fit.

The caddy or box 27 is placed in this press, said caddy having the bottom 28 secured therein by means of the conventional strips 29 and the fixed press head 30, which is smaller than the caddy is adapted to fit just inside these strips 29. The spongy, resilient fibrous pad 31 is then placed in the bottom of the box and the mass of pressed tobacco 33 is then placed in the caddy, then the second fibrous, resilient spongy pad 32 is placed on top of the mass of tobacco, and then the head member 35 is placed in position, and the movable head 34 of the press is driven down against the head member 35 and pressure is applied to cause the mass of tobacco to be further compressed to assume the condition shown in Figure 3, at which time the strips 36 and 37 are nailed in place to hold the head member 35 in position, and after the caddy is removed from the press, the other two strips are nailed in position to securely seal the caddy.

The mass of tobacco 33, after being pressed in press 16 Figure 1, can be placed with the spongy, resilient fibrous pads 31 and 32, in the caddy or box 27, as shown in Figure 2 either before or after the caddy or box 27 is placed in press for purpose of pressing and sealing into place head member 35 as shown in Figures 2 and 3.

While I have shown the press heads as being smooth in Figure 1, I desire it to be understood that my method can be used with even better results where the press heads in Figure 1 are uneven, but I have shown the press heads as being smooth for the reason that this is the conventional structure in thousands of presses now in use, and my invention is adapted to be used in connection with these presses without the necessity of

changing the structure of the presses, as this would entail great outlay of capital.

Also, I have shown the mass of tobacco not fully compressed in Figures 1 and 2, and I desire it to be understood that my invention and process can also be used where the tobacco is fully compressed, as when the pressure is relieved the back pressure will cause the mass of plugs to soon assume the position shown in Figures 1 and 2, and then when the mass is placed in the caddy and the caddy press as shown in Figure 3, the tobacco can be given a greater "pull" which will cause the outer surfaces of the plugs of tobacco next to the fibrous pads to impress their surfaces on the fibrous pads and the fibrous pads will in turn impress their surfaces on the proximate surfaces of the outer plugs of tobacco and in this way the fibrous pads will act similar to real plugs of tobacco, the main difference being in the cost of same, as the fibrous pads are made of ground vegetable material, exploded wood, and other suitable material which is very low in price and can be thrown away with little loss.

These layers of fibrous material are really dummy layers of material which act in the same manner as tobacco and may be composed of any suitable material other than tobacco.

The dummy layers 31 and 32 being between the plugs of tobacco and the head members of the caddy or box in which the tobacco is packed, receive, themselves on their outer surfaces the slick or unnatural finish of the head members in the caddy, and in this way the dummy layers thoroughly protect, at all times the outer surfaces of the end or outside plugs of tobacco from having a slick or unnatural finish imparted to them by the head members of the caddy or box.

In the drawings and specification I have set forth a preferred embodiment of my invention, and although specific terms are employed, they are used in a generic and descriptive sense only, and not for purposes of limitation, the scope of my invention being set forth in the appended claims.

I claim:

1. The process of pressing and packing tobacco which comprises placing a plurality of pieces of tobacco in a press and partially pressing the said pieces, then placing the partially pressed mass of tobacco in a container with fibrous resilient dummy layers next to the head members of the container, placing the container in another press and completing the pressing of the mass of tobacco and sealing the container while the tobacco is under pressure.

2. The process of pressing and packing manufactured tobacco which comprises pressing a series of pieces of tobacco in a press, placing a dummy layer in a caddy, placing the pressed tobacco in the caddy, placing a

dummy layer on top of the tobacco, placing a head member on said last mentioned dummy layer, placing the caddy in a second press, applying pressure thereto, and sealing the 5 caddy while the contents thereof are under pressure.

3. That process of pressing and packing manufactured tobacco which comprises placing the tobacco in a press, applying pressure thereto, removing the mass of pressed tobacco from the press, placing a fibrous, resilient, dummy layer in the bottom of a caddy, placing the pressed tobacco in the caddy, placing the caddy in a second press, placing a fibrous, 10 resilient, dummy layer on top of the tobacco, placing the head member of the caddy on the last mentioned dummy layer, further pressing the tobacco and dummy layers to a point where the caddy can be sealed by securing the 15 head member in position in the caddy.

4. That process of pressing and packing manufactured tobacco which comprises placing the tobacco in a press and applying pressure thereto, placing a caddy having a bottom 5 member in a second press, placing a dummy layer of material other than tobacco in the bottom of the caddy, placing the tobacco which has been pressed, in the caddy, placing a second dummy layer of material other than 10 tobacco on top of the tobacco, placing a head member for the caddy on the second dummy layer, applying pressure to the head member and the tobacco and the dummy layers and further pressing the same until the head member 15 can be secured in the caddy.

In testimony whereof I affix my signature.
HENRY P. TAYLOR.
